Primary Examiner — Mitchell Siegel

(57) **CLAIM**

The ornamental design for a golf club head, as shown and
described.

DESCRIPTION

FIG. 1 is a top perspective view of a golf club head;
FIG. 2 is a bottom perspective view of the golf club head of
FIG. 1;
FIG. 3 is a front elevational view of the golf club head of FIG.
1;
FIG. 4 is a rear elevational view of the golf club head of FIG.
1;
FIG. 5 is a top view of the golf club head of FIG. 1;
FIG. 6 is a bottom view of the golf club head of FIG. 1;
FIG. 7 is a left side view of the golf club head of FIG. 1;
FIG. 8 is a right side view of the golf club head of FIG. 1;
FIG. 9 is a top perspective view of a second embodiment of
the golf club head;
FIG. 10 is a bottom perspective view of the golf club head of
FIG. 9;
FIG. 11 is a front elevational view of the golf club head of
FIG. 9;
FIG. 12 is a rear elevational view of the golf club head of FIG.
9;
FIG. 13 is a top view of the golf club head of FIG. 9;
FIG. 14 is a bottom view of the golf club head of FIG. 9;
FIG. 15 is a left side view of the golf club head of FIG. 9; and,
FIG. 16 is a right side view of the golf club head of FIG. 9.
The broken lines connecting the solid lines represent the
bounds of the claim. The remaining broken lines illustrate the
environment. None of the broken lines forms part of the
claimed design.

1 Claim, 16 Drawing Sheets
